UNITED STATES PATENT OFFICE.

ERNST BÖHM AND WILLOUGHBY HAMILTON POWER, OF LONDON, ENGLAND.

DESIGN FOR A GLOBE.

SPECIFICATION forming part of Design No. 20,894, dated June 30, 1891.

Application filed March 19, 1891. Serial No. 385,692. Term of patent 14 years. Registered in England September 20, 1889, No. 14,855.

To all whom it may concern:

Be it known that we, ERNST BÖHM, manufacturer, of No. 53 Red Lion street, Clerkenwell, in the county of Middlesex, London, England, and WILLOUGHBY HAMILTON POWER, gentleman, of No. 20 Versailles road, Anerley, in the county of Surrey, London, England, subjects of the Queen of Great Britain, have invented and produced a new and original Design for the Glass Globes of Incandescent Electric Lamps, (for which we have obtained a patent in Great Britain, No. 14,855, dated September 20, 1889,) of which the following is a specification, reference being had to the accompanying drawings, which form a part thereof.

Figure 1 is a front elevation, and Fig. 2 a side elevation, illustrating our invention.

a is the glass globe of an incandescent electric lamp, and *b* its incandescent. The shape of the said incandescent forms no part of the present invention.

c *c* are two plano-convex lenses. They are counterparts of each other in respect of size and contour and are opposite each other upon the surface of the globe, which their plane sides touch.

d *d* are two annuli, one partly behind and partly around each lens. They are counterparts of each other in respect of both size and contour. Each is angular in cross-section, the front face (that next to the plane surface

of the lens) being plane, the back face (that next to the globe) being concave, as indicated in Fig. 1, and the third face of the annulus, which is the exposed face, is convex. Each 35 annulus occupies the annular space between the plane side *e* (indicated by the dotted line in Fig. 1) of the respective lens and the adjacent convex surface of the glass globe *a*, the adjacent edges of the said plane side of the 40 lens and of the third face of the annulus coinciding as shown.

We claim—

The design for the glass globe of an incandescent lamp herein shown, the same consisting of the surface of the globe, the convex surfaces of two plano-convex lenses opposite to each other, and the convex surface of two annuli extending from the edges of the lens to the convex surface of the globe, as set 45 50 forth.

In witness whereof we have hereunto set our hands, in the presence of two witnesses, this 8th day of January, 1891.

ERNST BÖHM.
WILLOUGHBY HAMILTON POWER.
